UNITED STATES PATENT OFFICE.

HENRY LEWIS GUY, OF MANCHESTER, ENGLAND, ASSIGNOR TO THE BRITISH WESTINGHOUSE ELECTRIC AND MANUFACTURING COMPANY, LIMITED, A COMPANY OF GREAT BRITAIN.

STEAM-TURBINE.

1,369,023.

Specification of Letters Patent. Patented Feb. 22, 1921.

Application filed June 29, 1916. Serial No. 106,651.

To all whom it may concern:

Be it known that I, HENRY LEWIS GUY, a subject of the King of Great Britain, and a resident of Manchester, in the county of 5 Lancaster, England, have invented a new and useful Improvement in Steam-Turbines, of which the following is a specification.

In axial flow steam turbines constructed to operate under a high vacuum the length 10 of the moving blades of the last stage may well be as much as two or three times the length of the moving blades of the preceding stage, and in the case of turbines designed to have a large output considerable practical 15 difficulties are experienced in providing moving blades for the last stage of such a length.

To overcome these difficulties it has been proposed to construct the last stage of the 20 turbine as a double stage in which the steam is divided into two annular portions or belts and flows in substantially the same direction through two separate rows of moving blades.

The present invention has for its object to 25 provide a turbine having a last stage of improved construction through which the flow of steam takes place in the above described manner.

According to this invention, of the two 30 annular portions into which the steam leaving the penultimate stage of the turbine is divided the outer portion flows through an annular steam supply chamber or belt to a row of fixed guide blades in which it is ex- 35 panded and then passes through a ring of moving blades to the turbine exhaust. The inner portion of the steam passes through a row of fixed guide blades in which the de- 40 sired expansion is effected and then through a ring of coöperating moving blades. From the latter the steam passes outwardly 45 through a plurality of transverse passageways contrived in the above mentioned annular chamber to the exhaust casing of the turbine.

With the construction above described each of the annular portions into which the steam leaving the penultimate stage is divided is caused to act on a separate ring of 50 moving blades without any substantial change in the direction of flow of the steam through said blades occurring.

The invention is applicable to turbines of either the impulse or reaction type and of

either disk or drum construction and will 55 now be described in greater detail with reference to the accompanying drawings which show, by way of example, an impulse turbine of disk construction to which the invention is applied. Figure 1 is a vertical longitudinal section of a portion of the low pressure stages of the turbine, and Fig. 2 is a transverse section taken on the line II—II of Fig. 1. Figs. 3 and 4 are sections on an enlarged scale on the lines III—III and 60 IV—IV respectively of Fig. 1.

In the turbine illustrated in Figs. 1 and 2 the high pressure portion, to which the present invention does not apply, is indicated at 5 and may be of any desired type and construction. In the low pressure portion, shown in section, the turbine shaft is indicated at 6 supported in a bearing or bearings 7 as usual. 8 is the exhaust casing and 9 the exhaust outlet leading to the condenser. Mounted on disks 10, 11 on the shaft 6 are rows of moving blades 12, 13 respectively between which is a coöperating row of stationary guide blades 14. The steam leaving the row of moving blades 13 65 is divided into two annular portions or belts by a circumferential rim or wall 15 forming part of the stationary diaphragm 16 which is provided with guide blades 18, 19 of any usual and well known construction. A disk 20 on the shaft 6 carries a row of moving blades 21, through which the steam passing 70 through the stationary guide blades 18, 19 75 flows. An annular steam conduit member 22 supported in the exhaust casing 8 by a web or diaphragm 23 conducts the outer portion of steam leaving the moving blades 13 to a row of stationary blades 24 secured in 80 the end of the steam chamber 22. A row of moving blades 25 attached to a disk 26 85 mounted on the shaft 6 coöperates with the stationary guide blades 24 and through 90 which the steam leaving said stationary blades passes. A plurality of transverse 95 passageways 27 (see Figs. 2 and 3) extend 100 through the conduit member 22 whereby steam leaving the blades 21 passes outwardly into the exhaust casing.

In operation the steam having passed through the high pressure portion of the 105 turbine and through the stationary and moving blades 12, 14, 13, is divided into two annular portions by the circumferential wall

15. The inner portion of steam, that is that portion of the steam nearest the turbine axis which flows within the rim or wall 15 through the stationary guide blades 18 and 5 19 and the moving blades 21, passes into the exhaust casing 8 through the transverse passageways 27.

The outer annular portion of steam leaving the moving blades 13, that is to say that 10 portion of the steam farthest from the turbine axis, flows through the annular steam conduit member 22 to the fixed guide blades 24 and thence through the row of moving blades 25 direct into the exhaust casing 8 of 15 the turbine.

The low pressure part of the turbine illustrated in the accompanying drawings is shown as being of the impulse variety and consequently the major part of the expansion 20 of the steam passing through the blading takes place in the stationary guide blades 14, 18, 19 and 24 as is usual, but it is to be understood that the accompanying drawings are typical of one form which the invention 25 may take when applied to an impulse turbine, as the invention may be applied to a reaction or other form of turbine and the constructional details of the turbine varied from what is shown, without departing from 30 the spirit and scope of the invention.

It will be obvious that my improvement is in a divided-flow, low-pressure turbine section whereby the low-pressure steam may be efficiently used. The divided-flow, low-pressure 35 section includes a stage having the blades 12, 13, 14 and a plurality of sets of low-pressure blading. The wall element 15 serves to divide the steam discharged from the stage comprising the blades 12, 13 and 40 14 into inner and outer annular portions, the inner annular portion being utilized by the nearer low-pressure blading and the outer annular portion passing through an annular conduit member 22 around the low-pressure 45 blading referred to and being utilized by other low-pressure blading arranged farther along the turbine axis.

Furthermore, in the drawings the inner and outer annular portions into which the 50 steam leaving the moving blades 13 is divided, have been shown as flowing respectively through one row of stationary and moving blades only. It is to be understood, however, that the invention is not limited in 55 this respect and that if desired the inner and outer portions of steam may each flow through two or more rows of stationary and moving blades if desired before passing into the exhaust.

60 I claim as my invention:

1. In a turbine, a divided-flow, low-pressure section comprising a stage, means to divide the steam discharged from said stage into inner and outer portions, low-pressure 65 blading receiving the inner portion of

steam, other low-pressure blading, and a conduit member for conducting the outer portion of steam to said other low-pressure blading.

2. In a turbine, a divided-flow, low-pressure section comprising a stage, means to divide the steam discharged from said stage into inner and outer annular portions, sets of low-pressure blading arranged along the turbine axis after said stage, means to conduct the inner annular portion of steam to the nearer low-pressure blading, and a conduit member serving to conduct the outer annular portion of steam to the farther low-pressure blading. 70 75 80

3. In a turbine, a divided-flow, low-pressure section comprising a stage, means to divide the steam discharged from the stage into inner and outer portions, low-pressure blading receiving the inner portion of 85 steam, other low-pressure blading, and a conduit member surrounding the first-mentioned low-pressure blading for conducting the outer portion of steam to the other low-pressure blading. 90

4. In a turbine, the combination of an exhaust casing and a divided-flow, low-pressure section, the latter comprising a stage, means to divide the steam discharged from said stage into the inner and outer portions, 95 low-pressure blading receiving the inner portion of steam, other low-pressure blading, a conduit member for conducting the outer portion of steam to the other low-pressure blading, and passageways extending through the conduit member to afford communication of the first-mentioned low-pressure blading with the exhaust chamber. 100

5. In a turbine, a divided-flow, low-pressure section comprising a stage, means for 105 dividing the steam discharged from said stage into inner and outer annular portions, low-pressure blading comprising co-operating stationary and moving blades receiving the inner annular portion of steam, other 110 low-pressure blading including stationary and moving blades, and an annular conduit member for conducting the outer annular portion of steam to the second-mentioned low-pressure blading. 115

6. In a turbine, the combination of an exhaust casing and a divided-flow, low-pressure section, the latter comprising a stage, means to divide the steam discharged from said stage into inner and outer annular portions, low-pressure blading receiving the inner portion of steam, low-pressure blading for the outer annular portion of steam, an annular conduit member for conducting the outer annular portion of steam to the 120 second-mentioned blading, means connected to the exhaust casing for supporting the conduit member in position, and passageways extending through the conduit member for affording communication of the first- 125 130

mentioned low-pressure blading with the exhaust casing.

7. In a turbine, the combination of an exhaust casing and a divided-flow, low-pressure section, the latter including a stage, two low-pressure sets of blading, a conduit member and diaphragm member supported by the exhaust casing at the end adjacent to said stage, a diaphragm carried by the exhaust casing and supporting the other end of the conduit member, a wall element carried by the first diaphragm and dividing steam discharged into inner and outer annular portions, the inner portion passing to

one set of low-pressure blading and the outer portion passing through the annular conduit member to the other set of low-pressure blading, and passageways extending through the conduit member to afford communication between the first set of low-pressure blading and the exhaust casing.

In testimony whereof, I have hereunto subscribed my name this thirteenth day of June, 1916.

HENRY LEWIS GUY.
